UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

DESIGN FOR A MOTOR-CYCLE HORN.

45,363.

Specification for Design.

Patented Mar. 3, 1914.

Application filed September 24, 1913. Serial No. 791,652. Term of patent 7 years.

To all whom it may concern:

Be it known that I, RAY H. MANSON, a citizen of the United States, residing at Elyria, in the county of Lorain and State of Ohio, have invented a new, original, and ornamental Design for Motor-Cycle Horns, of which the following is a specification, reference being had to the accompanying drawing, forming a part thereof.

The figures show my improved design.

Figure 1 is a side elevation of my improved design. Fig. 2 is a side elevation of my improved design.

I claim:—

The ornamental design for a motor cycle horn, as shown.

RAY H. MANSON.

Witnesses:

GEO. E. ROBERTS,
MARIAN VAUGHN.
